UNITED STATES PATENT OFFICE.

ELMORE ADELBERT HARRIS, OF NORWICH, CONNECTICUT.

BREECH-LOADING FIRE-ARM.

SPECIFICATION forming part of Letters Patent No. 394,691, dated December 18, 1888.

Application filed January 5, 1888. Serial No. 259,886. (No model.)

To all whom it may concern:

Be it known that I, ELMORE ADELBERT HARRIS, of Norwich, in the county of Chenango and State of New York, have invented a new and Improved Breech-Loading Fire-Arm, of which the following is a full, clear, and exact description.

This invention relates to breech-loading fire-arms, the object of the invention being to simplify the construction of such arms in the matter of the connection of the barrel with the stock and the arrangement of the extractors and firing-pins, and to form a stock allowing the use of a pair of barrels mounted one above the other.

Reference is to be had to the accompanying drawings, forming a part of this specification, in which similar figures of reference indicate corresponding parts in all the views.

20 Figure 1 is a side view of a portion of a gun constructed in accordance with the terms of my invention, the locks, however, not being shown in the view. Fig. 2 is a sectional plan view taken on line $x-x$ of Fig. 1. Fig. 3 is a view of the arm as it appears when the breech is unlocked and depressed to bring the extractors into play. Fig. 4 is a sectional view on line $y-y$ of Fig. 1, looking toward the muzzle of the gun; and Fig. 5 is a similar view 30 looking toward the stock of the gun.

The barrels of the fire-arm forming the subject-matter of this application are placed the one above the other, there being two rifled barrels, two shot-barrels, or a rifled barrel and 35 a shot-barrel, as shown in the drawings, the barrel 10 being a rifled barrel and 11 being a shot-barrel. From each side of the web by which these barrels 10 and 11 are connected there extends a trunnion, 12, and these trunnions 40 rest in horizontal slots 13, that are formed in side plates, 14, which constitute a portion of the stock 15.

Just in advance of the plates 14, I arrange other plates, 16, which have rearwardly-extending lips 17, that overlap the forward ends 45 of the plates 14, which forward-plate ends are circular, but are formed with a shoulder, 18, a corresponding shoulder, 19, being formed on the plates 16, the arrangement being such 50 that the two shoulders abut when the barrels are thrown to the position in which they are

shown in Fig. 3, thus limiting the oscillation of the barrels.

Through the web by which the barrels 10 and 11 are united I form a longitudinal bore, 55 20, in which there is mounted the shank 21 of an extractor, 22, the forward end this shank abutting against a transverse bar, 22^a, which extends through a slot, 24, that is formed in the web and carries plates 23. The upper 60 forward corners of the plate 23 are slightly cut away in order that they may be borne upon by the cam-faces 25 of the rearwardly-extending hooked ends of the plates 14, so that as the barrels are moved to the position 65 in which they are shown in Fig. 3 the extractor will be forced outward and to the rear. Above the cam-face 25 of the plates 14 is a lug, 25^a, which lugs, coming to a bearing on the plates 23, form stops coacting with the stops 18. 70

Through the stock 15, I insert a locking-dog, 26, which is normally forced forward by a spring, 27, that is coiled about its shank 28, said shank extending to the rear, there to be connected to a thumb-piece, 29. Notches 30 75 are formed in the butt of the web between the barrels, said notches being arranged for the reception of the teeth 31 of the locking-dog 26. In order that the dog may act automatically to lock the barrels to position, I incline 80 the upper faces of its teeth, and consequently when the barrels are thrown to the position in which they are shown in Fig. 1 the dog will be forced backward until the notches 30 come in register with the teeth, after which the spring 85 27 will act to force the dog forward and the teeth will engage said notches.

The firing-pins, the heads of which are shown at 33, are arranged in diagonal apertures formed in the stock, the one extending 90 upward toward the axis of the barrel 10, while the other extends downward toward the axis of the barrel 11, the arrangement being such that the parts are stored in an exceedingly compact manner.

Having thus fully described my invention, I claim as new and desire to secure by Letters Patent—

1. The combination, with a stock provided with forwardly-extending side plates adapted to receive the pivots of the barrels, of two vertically-aligning gun-barrels provided with

side trunnions centrally of the vertical line of the two barrels, substantially as set forth.

2. The combination, with a pair of gun-barrels mounted the one above the other and provided with side plates, one on each side, and with two trunnions, one on each side, of a stock provided with forwardly-extending plates which are recessed to receive the barrel-trunnions and to bear against the barrel-plates, substantially as described.

3. The combination, with a gun-barrel provided with side plates having overlying lips, of a stock, side plates connected thereto and passing beneath the side plates of the barrel, trunnions which rest in recesses formed in the side plates of the stock, an extractor, plates carried by a transverse bar against which the

extractor abuts, and rearwardly-extending cam-faced arms which bear against the plates, substantially as described. 20

4. The combination, with a pair of gun-barrels mounted the one above the other and pivotally connected to plates extending from the stock and having cam-faces 25, of a cross-bar, 22, extending transversely between the barrels, an extractor mounted between the ends of the barrels, provided with a shank abutting on the said cross-bar, and plates 23, carried by the cross-bar, substantially as shown and described. 25

ELMORE ADELBERT HARRIS.

Correction in Letters Patent No. 394,691.

It is hereby certified that the residence of the patentee in Letters Patent No. 394,691, granted December 18, 1888, upon the application of Elmore Adelbert Harris, for an improvement in "Breech-Loading Fire-Arms," was erroneously written in the grant and printed at the head of the specification Norwich, Connecticut; that said residence should have been written and printed *Norwich, New York*; and that the said Letters Patent should be read with this correction therein that the same may conform to the record of the case in the Patent Office.

Signed, countersigned, and sealed this 5th day of February, A. D. 1889.
